Primary Examiner — Wan Laymon(74) *Attorney, Agent, or Firm* — Oblon, Spivak, McClelland, Maier & Neustadt, L.L.P.(57) **CLAIM**

The ornamental design for a housing container for dental implant fixture, as shown and described.

DESCRIPTION

FIG. 1 is a front elevational view of a housing container for dental implant fixture;

FIG. 2 is a rear elevational view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a perspective view thereof with the cap separated from the housing main body;

FIG. 8 is an exploded view thereof; and,

FIG. 9 is a front and top perspective view thereof.

The broken lines in the drawings depict environmental subject matter only and form no part of the claimed design.
